UNITED STATES PATENT OFFICE.

ALEX TAUB, OF DETROIT, MICHIGAN, ASSIGNOR TO GENERAL MOTORS CORPORATION, OF DETROIT, MICHIGAN, A CORPORATION OF DELAWARE.

SPRING SUSPENSION.

Application filed March 7, 1927. Serial No. 173,384.

This invention relates to motor vehicles, and particularly to an improved form of resilient mounting or shackle connection between the chassis frame and vehicle spring.

5 An object of the invention is to provide a comparatively simple and inexpensive shackle connection, which will require little or no attention in use, eliminate the usual problems of lubrication, and which in operation will noiselessly cushion vibrations, road shocks or the like.

10 A further and important object of the invention is to provide a resilient mounting which will readily yield to permit relative movement of the spring and frame in a longitudinal direction, but will be resistant to the highly objectionable side sway between the parts.

15 Other objects and advantages will be apparent from the following detailed specification of a preferred embodiment of the invention, taken in connection with the accompanying drawing, in which—

20 Figs. 1 and 2 are detail views, partly in section and partly in elevation, showing respectively the connections between opposite ends of the rear spring with the chassis frame.

25 Referring more specifically to the drawing, the reference character 1 represents one of the longitudinally extending channeled side members of the chassis frame, which terminates at its rear end in a horn or down-turned portion 2, and 3 indicates a semi-elliptical multi-leaf spring to flexibly support the frame on the rear axle. While reference herein is only made to one of the rear springs, it will be obvious that the same shackle connections are for use with each 30 of the vehicle springs, both at the front and the rear.

40 The driving connection for the front end of the spring 3 is illustrated in Fig. 1, which constitutes a pivotal mounting therefor. In this case, there is provided a block of cushioning material, preferably consisting of a body of rubber or other elastic substance 4, having integrally embedded therein by vulcanization or the like, a link or strap 5 of flexible, but inextensible material, such as 45 fabric cloth or fibrous material, or if desired, this strap may be formed of thin sheet metal having a comparatively high degree of resiliency. A retainer cup 6, pressed or 50 stamped from sheet metal, is riveted or bolted

55 at 7, to the bottom flange of the channel frame member 1, and the cushioning block is contained within this cup, and may be placed therein under a slight initial compression. The flexible strap 5 is bowed upwardly, due 60 either to preformation or deformation of the block within the cup, and a fastening bolt 8 passes upwardly through the block at the bight of the bowed strap and is secured to the bottom flange of the frame member 1 by 65 a nut 9. Spaced longitudinally on either side of the bolt 8 are fastening bolts 10—10 extending downwardly through the block at opposite ends of the strap 5, being secured to the front end of the spring 3 by nuts 11—11. 70 The strap 5 within its elastic envelope 4 thus provides a link between the spring and frame, which, since it is inextensible, does not permit side sway or relative transverse movement between the longitudinally spaced 75 fastening bolts. However, the bow or longitudinal undulation in the strap allows its inherent flexibility to act in a longitudinal direction to permit slight relative turning of the fastening bolts 10 in respect to the bolt 8, forming in effect a pivot between the frame 80 and front end of the spring.

85 In order to compensate for extension of the vehicle spring 3 upon deflection, the mounting for the rear end of the spring is slightly different from the mounting at the front end, as shown in Fig. 2. Here the retainer cup 12, riveted or bolted as at 13 to the bottom of the horn 2, is provided at either end with an in-turned ear or channel portion 14 into which channels are inserted ribs or beads 15 of the resilient block. The elastic cover 16, surrounding the bowed or undulating strap 17, extends beyond the ends of the strap for some distance, and is preferably 90 provided with transverse openings 18, which serve to increase its elasticity and facilitate longitudinal distortion. The fastening bolt 19 extends through the block at the bight of the strap 17, and is secured to the spring end by nut 20. Here again, the bowed strap 17 reinforces the block against side sway, but readily yields or flexes with the longitudinal distortion of the elastic body 16, upon deflection and extension of the vehicle spring 3. 95

100 While the subject matter has been described more or less specifically in its preferred form, it is to be understood that the invention is not limited to the exact details set forth, but that such modifications may be 105 110

made as come within the scope of the appended claims.

Having described my invention, I claim:

- 5 1. In a motor vehicle, the combination with a chassis frame and a vehicle spring, of flexible connections between the ends of the spring and the frame, including elongated blocks of elastic material, longitudinally undulated fabric reinforcement strips embedded within the material, retainers for said blocks carried by one of the members to be connected, and fastening bolts extending through the blocks and passing through both the elastic material and the embedded fabric
- 10 15 and secured to the other of said members to be connected.
- 20 2. In a motor vehicle, the combination with a chassis frame and a load supporting spring, of a hinged connection therebetween, including a bowed flexible link having its opposite ends secured to one of said parts and its bight secured to the other of said parts, and elastic cushioning material interposed between the link and said parts.
- 25 3. In a motor vehicle, the combination with a chassis frame and a load supporting spring, of a hinged connection therebetween, including a bowed flexible link and a relatively thick envelope of elastic cushioning material surrounding said link, means securing the opposite ends of the link to one of said parts and means securing the intermediate bight thereof to the other of said parts.
- 35 40 4. In a motor vehicle, the combination with a chassis frame and a load supporting spring, of a flexible connection therebetween, including a block of elastic cushioning material and a flexible but inextensible strap integrally united with said block, said strap being bowed in the direction of relative movement

of the parts, a container for the block carried by one of the parts, and a fastening element associated with the block at the bight of said bowed strap and secured to the other of said parts.

5. In a motor vehicle, the combination with a chassis frame and a load supporting spring, of a flexible connection therebetween, including a block of elastic material and a bowed strap of flexible fabric embedded within said elastic material, means to secure the ends of the block to one of the parts, and means to secure an intermediate portion of the block at the bight of the bowed fabric strap to the other of said parts.

6. In a motor vehicle, the combination with a chassis frame and a load supporting spring, of a flexible connection therebetween, including a block of elastic material, a flexible but inextensible strap embedded within said elastic material in undulating relation throughout its longitudinal extent, and means to secure the block to the respective parts at longitudinally spaced apart points.

7. In a motor vehicle, the combination with a chassis frame and a vehicle spring, of a flexible connection therebetween including a block of elastic resilient cushioning material secured to said parts at longitudinally spaced apart points, said block having transverse openings therein to increase the degree of resiliency in a longitudinal direction, and a flexible but inextensible reinforcing strap integrally united and embedded within said elastic block in longitudinal undulating relation, said strap yielding to relative longitudinal movements but resisting relative transverse movements between said parts.

In testimony whereof I affix my signature.
ALEX TAU B.
